UNITED STATES PATENT OFFICE.

JACOB ALBRIGHT, OF DETROIT, MICHIGAN, ASSIGNOR TO THE ELECTRIC GAS STOVE COMPANY, OF SAME PLACE.

BROILER.

SPECIFICATION forming part of Letters Patent No. 597,349, dated January 11, 1898.

Application filed August 9, 1895. Serial No. 558,748. (No model.)

To all whom it may concern:

Be it known that I, JACOB ALBRIGHT, a citizen of the United States, residing at Detroit, county of Wayne, State of Michigan, have invented a certain new and useful Improvement in Broilers; and I declare the following to be a full, clear, and exact description of the invention, such as will enable others skilled in the art to which it pertains to make and use the same, reference being had to the accompanying drawings, which form a part of this specification.

This invention relates to gas-burning broilers, and has for its object an improvement in that class of broilers in which the article to be cooked is exposed between two plates or burners over which are scattered a large number of small gas-jets, thus producing a sheet of flame parallel to the side of the article.

This invention relates to the proper conveyance of gas from the main to the burner or jet holes, to the material employed as the plate perforated for burner or jet holes, and to provision for a second supply of air in addition to that received at the mixer for the proper combustion of the gas.

Broilers of this class are usually arranged with the burner-plates vertical—that is, the burner-jets are scattered over two of the vertical walls and are directed inward. A supply of air from the bottom of the case passing upward along the burners affords sufficient oxygen for a few of the jets along the bottom of the plate, but is soon deprived of oxygen and charged with products of combustion, so that the upper jets of flame do not get a sufficient supply and burn poorly.

Another improvement relates to the material through which the jet-holes are made. The jet-holes are small, and when iron or brass is used they quickly fill up with a deposit. Especially is this so where natural gas is used as a fuel, and I have found that by using thick asbestos board instead of metal the holes will remain clear for a long period of time.

In the drawings, Figure 1 is a front elevation. Fig. 2 shows the burner-plate, a portion only of the plate being shown. Fig. 3 is a sectional elevation across the broilers,

the section being taken across the broiler at line *xx* of Fig. 4. Fig. 4 is a side elevation, a part only of one side being shown.

The broiler is made in a substantially rectangular box or stove, with a base *A* and cap-plate *B*, provided with an outlet *b* for the escape of products of combustion, the outlet having a collar *b'*, upon which to seat a pipe, if desired. The bottom is preferably closed by a sheet of thin metal *a*, and one of the ends or narrow sides is closed by folding doors *C C*, provided at their meeting edges with openings *c c*, through which the handle of a grid can project. Provision is made at the bottom for a drip-pan *D*.

The sides *2 2* of the broiler contain the main features of the invention. They are exactly alike except that one is a right and the other a left side. The side *2* is made with connections, so that on the outside it takes the form of a vertical half-pipe *3*, into which leads an inlet *4* and out of which lead a number of horizontal half-pipes or fingers *5* on the inside of the plate *2*. The upright half-pipe and fingers are concave, and they are united by the main plate, which forms a web between adjacent fingers *5*. The inner faces of these webs and the inner face of that part of the plate which surrounds the upright and fingers are all in one plane, the whole plate being surrounded by proper engaging grooves and flanges, by means of which the several plates constituting the structure can be securely held together by concealed bolts. The upright half-pipe *3* at the bottom has an inlet *4*, which is completely tubular in form and is adapted to receive and hold the mixer-mouth *7*, this being any approved form of mixer adapted to mingle air and gas. The tubular structure of the upright *3* and fingers *5* is completed by a sheet of asbestos held in any suitable way, as by bolts *8 8 8*, to the plate *2*, and engaging closely with the inner face of the plate and with the inner faces of the web portions of the plate between the fingers *5 5*. Along the inner plate are rows of jet-holes *9 9*, which perforate the inner plate and enter the tubular cavities *10 10* under the fingers *5*. Between the fingers *5*, through both the web and the inner plate, are air-inlet openings *12*.

12. Across the inner plate and just above the gas-jet openings 9 9 are rows of fibrous asbestos held to the inner plate by cement or in any other suitable way. These layers 5 of fibrous asbestos would tend to prevent a free access of secondary air from below, and when the fibrous asbestos is used the inlet-openings are particularly useful.

10 F F indicate arms adapted to support the grid.

I would have it understood that while I deem it very desirable to use asbestos for the inner plate a metal plate would work, and if given attention in the way of keeping it 15 clean would be satisfactory for a long time.

What I claim is—

1. In a broiler the combination of a plate provided with corrugations spaced by a uniting-web, a plate adapted to engage over the

corrugations and against the web, said web 20 being perforated and said plate being provided with perforations registering with the perforations through the web and with gas-jet perforations leading through the plate into the tubular cavity formed by the corrugation and plate.

2. In a burner for broilers, the combination of a tubular gas-conductor perforated with gas-jet openings, air-inlet openings arranged beneath the jet-openings and a layer of asbestos fiber disposed above the openings, substantially as described.

In testimony whereof I sign this specification in the presence of two witnesses.

JACOB ALBRIGHT.
